RESILIENT MESH MATERIAL

Howard F. Weiss, deceased, late of Madison, Wis.,
by Nelle E. Weiss, executrix, Madison, Wis., as-
signor, by mesne assignments, to Research
Products Corporation, Madison, Wis., a corpo-
ration of Wisconsin

Application May 6, 1941, Serial No. 392,108

17 Claims. (Cl. 117—98)

This invention relates to a resilient sheet material and particularly to a soft, flexible, resilient, mesh material which is adapted for making pads, cushions, gaskets and the like, and which has a high coefficient of friction whereby it may be used for antiskid purposes, as for example, for non-slip mats or rugs and non-slip pads for under carpets and rugs, and the like.

Rubber pads and cushions have been used heretofore for similar purposes, and it is the object of the invention to provide a new article having improved properties for such purpose.

Briefly, the invention consists in forming a fabric in the form of a slitted and expanded sheet composed at least chiefly of rubber, or a material which has the softness, flexibility and resilience of vulcanized soft rubber. In a fabric of such form, the network is composed of thin, substantially flat, strip-form sections having their broad surfaces disposed angularly to the general plane of the fabric, and when it is composed of a non-rigid resilient material, the result is a product having a relatively high degree of softness and resilience. When the fabric is composed of a material such as vulcanized soft rubber, the resulting fabric possesses softness and resilience in a very high degree and makes an excellent cushioning and padding material.

In accordance with the invention, the fabric is made by applying a coating of a rubber dispersion to a support in the form of slitted and expanded thin sheet material, such as paper, and coagulating and drying the rubber in situ to form a composite fabric having an exterior portion composed of rubber and an interior core composed of the slitted and expanded supporting sheet material.

In the drawings:

Fig. 1 is a plan view of a section of the resilient sheet material of this invention;

Fig. 2 is a fragmental sectional view along line 2—2 of Fig. 1;

Fig. 3 is a diagrammatic illustration of an apparatus and method for making the resilient sheet material.

Figs. 4 and 5 are fragmental sectional views of modified forms of the resilient sheet material, and

Figs. 6 and 7 are side views of different forms of mats or cushions composed of a plurality of layers of the resilient sheet material.

The resilient sheet material shown in Fig. 1 is an open-mesh fabric in the form of a slitted and expanded sheet 10. The fabric is composed of a network of thin, substantially flat, strip-form

sections or webs 11 whose broad surfaces are disposed angularly to the general plane of the fabric. As shown in Fig. 2, the webs 11 are composed of a core 12 of supporting material, preferably readily flexible, such as paper, and an exterior portion or covering 13 of vulcanized soft rubber, or other material having the softness, flexibility and resilience of vulcanized soft rubber. By the term "soft rubber" it is meant to distinguish from rigid hard rubber. The angular orientation of the webs 11 is caused by expanding the slitted sheet transversely of the slits, during which action the webs are turned so that the plane of each individual web is at a substantial angle to the general plane of the fabric. When the fabric is subjected to compressive forces exerted perpendicularly to its general plane, it yields by reason of a bending of the webs, which is resisted by their resilience. There is, therefore, an inherent resilience or cushioning effect in a fabric of such character. This cushioning effect, in general, increases with the degree of expansion. When a non-stretching material such as paper is used as the expanded supporting means, there is a maximum degree of expansion which may be reached without rupturing the supporting member.

When the fabric is composed of a material having the degree of softness, flexibility and resilience which is possessed by vulcanized soft rubber, the fabric is characterized by ready flexibility and a cushioning effect of an exceptionally high order. The fabric possesses high tensile strength and resistance to abrasion. In addition, vulcanized soft rubber possesses a high coefficient of friction, and the fabric is very resistant to slipping, even when in contact with smooth and slippery surfaces. The product of this invention has the additional advantage that the pattern of the fabric, that is, the size and shape of the openings and the length, width and thickness of the webs, may be varied to suit different applications. In a modification of the invention, the apertures of the expanded fabric are closed over with thin rubber films with resulting modification of properties. This will be described more in detail hereinafter.

In accordance with the present invention, the resilient material is made by applying a coating of rubber to a supporting fabric of slitted and expanded sheet material, preferably composed of a material which is readily flexible, such as paper, regenerated cellulose, cellulose acetate, cellulose hydrate, cellulose ethers and esters and other substances of cellulose base, in film or sheet form, woven or felted cloth, which may be reinforced

and strengthened by impregnating with glue, regenerated cellulose or other film-forming material, oil cloth, sheet asbestos, and the like. The material should not be extensible in the manner in which elastic rubber is extensible. As an example, 60 pound kraft paper is a satisfactory material. The slitted and expanded sheet material may be supplied in the desired width and length. If it is of an inherently resilient material, such as paper, whereby it tends to return to the unexpanded condition, it may be fixed or set in the expanded condition in any suitable manner. Expanded paper may be set by causing it to be moistened and then dried while in the expanded condition, or by applying stiffening materials to it, such as glue, resins, etc.

As is illustrated in Fig. 3, the expanded supporting material 19 may be supplied in the form of a roll 20 thereof and fed from the roll over a series of supporting and guide rolls 21, while operations are performed which will be described. The sheet first passes into a rubber coagulating bath 22 which may be a dilute aqueous solution of any suitable coagulating agent. An example is a water solution containing 10% calcium chloride, 5% acetic acid and a small amount of a wetting agent, such as soap. Calcium chloride or acetic acid may be used alone and other known rubber coagulating agents may be used. The expanded sheet is coated and impregnated with the coagulating solution, and thence passes into a bath of rubber latex dispersion 23. A water dispersion containing approximately 50% solids and 0.2% ammonia, is satisfactory, and it may contain a dye or pigment if it is desired to impart a color to the product. It may also contain fillers to impart desired characteristics, such as comminuted reclaimed rubber, silica, asbestos, carbon black, or any other filler commonly employed in rubber products. Dispersions may be employed containing different concentrations of solids from that described. The latex may be in either the prevulcanized or unvulcanized condition. If it is in the prevulcanized condition, it need only be dried to be formed into the final vulcanized soft rubber product. If it is in the unvulcanized condition, it preferably contains the sulfur compounds and accelerators required for vulcanization and may be cured by subjecting it to an elevated temperature. A temperature of 80° C. is sufficient and may be applied simultaneously with the subsequent drying operation. In the specific method described, a dispersion of prevulcanized latex is employed. A coating of the latex dispersion is applied to both sides of the slitted and expanded supporting material during the dipping operation. The thickness of the coating depends upon the viscosity of the latex dispersion and uniform thickness can best be obtained by maintaining uniform the viscosity, rather than the content, of the dispersion. In this way, non-uniformity in the character of the latex which is sometimes encountered does not affect the coating thickness.

The latex dispersion tends to bridge over and fill the apertures of the expanded supporting material, and when a dispersion of the concentration described is used, the apertures are substantially all closed over. To remove the dispersion from the apertures the coated sheet is now passed between a series of air blasts 24. Air under pressure is supplied to conduit system 25 from a source which is not shown. The coated sheet passes vertically downward and the air blasts strike it alternately from opposite sides as it travels. The

dispersion is removed from the apertures, and shallow trays or troughs 26 are provided which catch the resulting spray of dispersion and conduct it to a point from which it may be reclaimed for further use.

From the air blasts 24 the coated expanded material is conducted to a second coagulating bath 27 which may be of the same composition as coagulating bath 22. Because of the two applications of coagulating agent, coagulation of the latex proceeds from the interior as well as the exterior of the rubber coating. To rid the coating of excess coagulating solution, an air blast 28 is directed against the coated material as it leaves the coagulating bath. The air blast is arranged, as shown, so as to return the excess to the coagulating bath.

From the coagulating bath, the coated expanded material is conducted into a water bath 29, where it is washed substantially free of coagulating agent. After it leaves the washing bath it is sprayed with clean water from a spray pipe 30 to further cleanse it of coagulating agent. The spray water is caused to fall into the water bath and the latter is provided with an overflow conduit 31. The washed sheet may then be subjected to an air blast 32 to remove some of the water which clings to it.

Thence the coated, expanded material passes to a drier 33 which it is caused to traverse in a suitable manner to accomplish the desired drying of the material. In the particular drier illustrated, the material is conveyed therethrough by means of a plurality of conveyors 34 to which it passes in succession. Drying air or gas, preferably heated to an elevated temperature, is circulated through the drier, and the conveyors 34 are composed of an open-mesh material or a plurality of spaced longitudinal strands and permits the ready passage of the drying gas therethrough. If an unvulcanized rubber is used, the material is subjected to curing conditions in the drier.

The dried resilient material emerges from the drier 33 and may be accumulated in the form of a roll 35 from which it may be taken for use or sale. The drying need not be entirely completed in the drier 33, it being sufficient if the material is dried to the point where the adjacent layers will not stick together when it is rolled up on the roll 35. The remainder of the drying is then carried out while the material is in storage. The material being of an open-mesh character, the air circulates freely through it and the roll of material is dried uniformly throughout.

When the above described method for forming the resilient sheet-form material is employed and applied to 60 pound kraft paper, which has a thickness of .006 inch, the thickness of the product is .022 inch, and the rubber coating applied to each side of the expanded sheet has a thickness of .008 inch.

The specific method described is illustrative only, and the details thereof may be varied as desired. For example, instead of applying the coating of latex to the supporting slitted and expanded sheet by a dipping operation, it may be applied by spraying the latex solution against one or both sides of the expanded sheet.

Where the rubber is applied to only one side of the supporting slitted and expanded sheet material, the supporting sheet may be separated from the rubber fabric after the formation of the latter is complete. This may be done by mechanical means, or where an expanded paper

supporting sheet material is employed, by washing the fabric with water, which will cause the disintegration of the paper. A fabric 38 of this character is shown in Fig. 4.

As another variation of the method, the blowing of air blasts through the sheet material following the coating operation may be eliminated. This will result in thin films of rubber remaining in the apertures of the expanded material. Such a product has particular application where it is desired that the passage of air or gas through it be obstructed or prevented. The softness and resilience of the product is affected but slightly by the presence of the thin films. A product of this character is illustrated in Fig. 5, where the network of the expanded material is indicated at 40 and the thin films at 41.

In the described method, the first application of coagulating agent causes a setting or coagulating of the coating to proceed from the interior outwardly and with proper regulation of the rate of travel of the material this may be caused to proceed to the point where further coagulation is unnecessary and the material may pass directly from the air blasts 24 to the drier 33, and the second coagulating bath may be dispensed with. In a similar manner, the first coagulating bath may be dispensed with. The employment of two coagulating baths, as described, enables the more rapid carrying out of the process, and imparts a desirable increase in firmness whereby the main portion of the coating is less disturbed while the films are being removed by the air blasts. As a further alternative, instead of employing the first coagulating bath 22, the slitted and expanded sheet material may be impregnated with a coagulating agent at a previous time so that it is in pre-impregnated condition at the beginning of the process.

A plurality of layers of the resilient material may be assembled to form a relatively thick pad or cushion. In Fig. 6 a product is illustrated which is composed of a plurality of superposed layers 50 of the resilient material, joined together by a suitable adhesive, such as rubber cement. The layers may also be joined together by means such as staples, stitching or sewing, etc. The layers may all be of the open-mesh type or of the closed mesh type or a combination may be employed in which some of the layers are of one type and others of the other. For example, the closed and open mesh layers may be arranged in alternating succession.

In Fig. 7 a further modification is illustrated in which layers of the resilient material 55 are arranged in alternating succession with plain imperforate or perforated sheets 56, which may be of rubber, paper, cloth or other sheet material.

In the foregoing description of the invention, rubber is employed as the chief material of which the resilient product is composed, but it is to be understood that other materials having comparable softness, flexibility, resilience and adhesive properties may be used as well. A suitable material is the synthetic rubber made from polymerized isoprene, which has substantially the same properties for the purposes of this invention as does vulcanized soft rubber. The method for applying the synthetic rubber is substantially the same as that described heretofore. When the term "rubber" is used herein in the specification and claims it is intended to include such other materials, as synthetic rub-

ber, having properties similar to those of natural rubber.

What is claimed is:

1. As a new article of manufacture, a pre-formed network of rubber having the form of a slitted and expanded sheet.
2. As a new article of manufacture, a resilient sheet-form product comprising a preformed network having the form of a slitted and expanded sheet, said network being composed essentially of rubber.
3. As a new article of manufacture, a resilient sheet-form product comprising a preformed apertured network having the form of a slitted and expanded sheet, said network being composed essentially of rubber, at least some of the apertures of said network being closed over with thin films of rubber.
4. As a new article of manufacture, a resilient sheet-form product, said product comprising a network of thin substantially flat, strip-form sections having their broad surfaces disposed angularly to the general plane of the fabric, said network being composed essentially of rubber.
5. As a new article of manufacture, a composite resilient sheet-form product, comprising slitted and expanded sheet material having the flexibility of paper and a coating of rubber on said expanded material.
6. As a new article of manufacture, a composite resilient sheet-form product, comprising a slitted and expanded fibrous sheet, and a coating of rubber on said expanded sheet.
7. As a new article of manufacture, a composite resilient sheet-form product, comprising a slitted and expanded sheet of material having a cellulose base, and a coating of rubber on said expanded sheet.
8. As a new article of manufacture, a composite resilient sheet-form product, comprising a slitted and expanded paper sheet, and a coating of rubber on said expanded sheet.
9. As a new article of manufacture, a composite resilient sheet-form product, comprising a network of thin, strip-form sections having their broad surfaces disposed angularly to the general plane of the sheet, said network being composed of a material from the group consisting of fibrous and cellulose base materials, and a coating of rubber on said network.
10. As a new article of manufacture, a mat comprising a plurality of layers, each layer comprising a preformed network having the form of a slitted and expanded sheet and being composed essentially of rubber.
11. The method of making a resilient sheet-form product, which comprises coating slitted and expanded sheet material from the group consisting of fibrous and cellulose base materials with an aqueous dispersion of rubber, blowing gas through said coated sheet material to open apertures thereof which may have been filled by said dispersion, contacting said coating with a rubber coagulating agent, and subsequently water washing and drying said coated sheet material.
12. The method of claim 11 in which the blasts of gas are blown alternately against opposite sides of the coated sheet material.
13. The method of making a resilient sheet-form product, which comprises dipping slitted and expanded sheet material from the group consisting of fibrous and cellulose base materials into an aqueous dispersion of rubber to coat both sides of said sheet material with said dispersion, coagulating said dispersion on said expanded sheet

material, and drying said coating on said sheet material.

14. The method of making a resilient sheet-form product, which comprises coating slitted and expanded sheet material having the flexibility of paper with an aqueous dispersion of rubber, and drying said coating on said sheet material.

15. The method of making a resilient sheet-form product, which comprises coating one side of a slitted and expanded sheet material with an aqueous dispersion of rubber, coagulating said dispersion on said expanded sheet material, drying said rubber coating, and separating said rubber coating from said expanded sheet material.

16. The method of making a resilient sheet-form product, which comprises applying a coating

of rubber to slitted and expanded sheet material having flexibility substantially equal to that of paper.

17. The method which comprises coating with an aqueous dispersion of particles of rubber an open-mesh network of thin, substantially flat, strip-form sections having their broad surfaces disposed angularly to the general plane of the network, said network being composed of a material from the group consisting of fibrous and cellulose base materials, and coagulating said particles to leave a coating of rubber upon said network.
